(57) **CLAIM**

An ornamental design for a distribution housing, as shown and described.

DESCRIPTION

FIG. 1 is a front view of a first embodiment of a distribution housing;

FIG. 2 is a right side view of the distribution housing of FIG. 1;

FIG. 3 is a left side view of the distribution housing of FIG. 1;

FIG. 4 is a rear view of the distribution housing of FIG. 1; FIG. 5 is a top view of the distribution housing of FIG. 1; FIG. 6 is a bottom view of the distribution housing of FIG. 1;

FIG. 7 is a front view of another embodiment of the distribution housing;

FIG. 8 is a right side view of the distribution housing of FIG. 7;

FIG. 9 is a left side view of the distribution housing of FIG. 7;

FIG. 10 is a rear view of the distribution housing of FIG. 7; FIG. 11 is a top view of the distribution housing of FIG. 7; and,

FIG. 12 is a bottom view of the distribution housing of FIG. 7.

The elements shown in phantom, which are depicted as dash-dash-dash lines, are for illustrative purposes only and do not form part of the claimed design.

1 Claim, 8 Drawing Sheets
